UNITED STATES PATENT OFFICE.

DEXTER W. GOODELL, OF GREENFIELD, MASSACHUSETTS, ASSIGNOR TO
J. WILLIS DOWNS, OF NEW HAVEN, CONNECTICUT.

DESIGN FOR A SEWING-MACHINE FRAME.

SPECIFICATION forming part of Design No. 26,847, dated March 30, 1897.

Application filed February 18, 1897. Serial No. 624,059. Term of patent 14 years.

To all whom it may concern:

Be it known that I, DEXTER W. GOODELL, of Greenfield, in the county of Franklin and State of Massachusetts, have invented a new 5 Design for a Sewing-Machine Frame; and I do hereby declare the following, when taken in connection with the accompanying drawings and the letters of reference marked thereon, to be a full, clear, and exact description of the 10 same, and which said drawings constitute part of this specification, and represent, in—

Figure 1, a view in side elevation; Fig. 2, a top view; Fig. 3, an end view.

This invention relates to a design for sewing-machine frames; and the design consists 15 in the configuration as hereinafter described, and shown in the accompanying illustrations.

As herein shown, the frame has a flat plate A, rounded at one end and squared at the 20 opposite end. From the squared end rises a post B, having an arm C, which projects over

the base. The forward end of the arm has guideways D and E, and from its rear face project rocker-shaft bearings F G. Near the bearing E is a tension-support H. The upper 25 end of the post B has a flat face I, and extending outward from its edge is an offset J for the spool-support. In the under face of the plate are shaft-supporting lugs K and L, all as shown in the accompanying illustrations. 30

I claim—

The design for a sewing-machine frame as herein shown and described.

In testimony whereof I have signed this 35 specification in the presence of two subscribing witnesses.

D. W. GOODELL.
